UNITED STATES PATENT OFFICE.

WILLIAM G. RALSTON, OF EVANSVILLE, INDIANA.

DESIGN FOR A BED-WARMER.

SPECIFICATION forming part of Design No. 26,527, dated January 12, 1897.

Application filed August 7, 1896. Serial No. 602,085. Term of patent 7 years.

To all whom it may concern:

Be it known that I, WILLIAM G. RALSTON, a citizen of the United States, residing at Evansville, in the county of Vanderburg and State of Indiana, have invented and produced a new and original Design for Bed-Warmers; and I do hereby declare the following to be a full, clear, and exact description of the same.

10 This invention relates to a design for hot-water-heating devices, but more particularly to bed-warmers.

15 My design consists, essentially, in a bed-warmer having the form or configuration substantially as shown in the accompanying drawings, that is to say, the body thereof is elongated and substantially semicircular in cross-section and provided with inclosing end pieces and a smooth exterior, except that at 20 one end it has a handle and on top a throat or projection having a cap provided with a spiral or curved body fitting similar spirals or curves thereon. Thus it will be seen the leading features of the design reside in the 25 elongated semicircular shape or configuration of the bed-warmer body provided with a smooth exterior surface and a throat or projection at one end on which is a cap or cover having a spiral or curved body portion and a 30 handle projecting from said end.

In the accompanying drawings, forming a part of this specification, Figure 1 is a perspective view of the bed-warmer, and Fig. 2 is a transverse sectional view of the same.

Referring to said drawings, the body A 35 may be elongated and is approximately semicircular in cross-section, being formed with a substantially flat lower surface or bottom a and an arched or curved portion a', provided with inclosing end pieces a², which are 40 preferably slightly curved or bulged outwardly. The arched or curved portion is provided at the top thereof with a tubular throat or projection b, having an apertured cap b', provided with a spiral or curved body 45 b², fitting over similar spirals or curves on the throat or projection. A suitable handle b³ may be arranged upon one of the end pieces, so as to permit the warmer to be readily moved or transported. 50

What I claim is—

The design for a bed-warmer substantially as herein shown and described.

In testimony whereof I affix my signature in presence of two witnesses.

WILLIAM G. RALSTON.
